UNITED STATES PATENT OFFICE.

EZECHIEL WEINTRAUB, OF SCHENECTADY, NEW YORK, ASSIGNOR TO GENERAL ELECTRIC COMPANY, A CORPORATION OF NEW YORK.

RECTIFYING ALTERNATING CURRENT.

1,134,786.

Specification of Letters Patent.

Patented Apr. 6, 1915.

Application filed March 23, 1903. Serial No. 149,084.

To all whom it may concern:

Be it known that I, EZECHIEL WEINTRAUB, a subject of the Czar of Russia, residing at Schenectady, county of Schenectady, State 5 of New York, have invented certain new and useful Improvements in Rectifying Alternating Current, of which the following is a specification.

My invention relates to the rectification 10 of alternating current and comprises various improvements in the construction and arrangement of the rectifying apparatus and in the circuits and systems of distribution in connection with which the apparatus may 15 be employed.

In rectifying alternating current I make use of a property, discovered by me, that a vapor, such for example as the vapor of mercury, produced in an exhausted receptacle by means of electrical energy passed into said receptacle through electrodes suitably located therein, is a conductor for current flowing in one direction through the vapor and a non-conductor for current tending 25 to flow in the opposite direction. Due to this unsymmetrical conducting character of the medium an alternating electro-motive force, when impressed upon such electrodes, causes a unidirectional current to flow between the electrodes. As I have set forth in my copending application, Serial No. 149,083, filed concurrently herewith, the luminous character of the vapor renders my invention also useful in the production of light, in which case, of course, the size and shape of the exhausted receptacle may be chosen accordingly.

The various features of novelty which characterize my invention I have pointed out 40 with particularity in the appended claims. The invention itself, however, will be best understood by reference to the following description taken in connection with the accompanying drawings in which—

45 Figures 1, 2, 3, and 4 represent the application of my invention to the rectification of single phase alternating current while Figs. 5 and 6 represent modifications of the invention shown in Fig. 1, and Fig. 7 represents a modification of the invention shown 50 in Fig. 2.

In Fig. 1 which represents one of the simpler forms of a rectifying apparatus, made in accordance with my invention, I em-

ploy a receptacle 1 of any suitable form and 55 made of a material such as glass, or fused quartz or silica. Other materials may however be chosen, such for example as metal, in which case the receptacle should be coated either inside or outside or both with a hard 60 glaze impervious to air. If metal alone were used, the extremely high vacuum which it is necessary to maintain in the receptacle in order to obtain the best results is liable to slow deterioration through leakage of air 65 through the pores of the metal. This leakage has only to be very slight in order to impair the vacuum. I find it convenient however in order to observe the working of the apparatus to make a receptacle of some 70 light-conducting material such as heretofore mentioned. The shape of the envelop may be widely varied without departing from my invention. In Fig. 1, the receptacle or envelop is represented as a somewhat squatly 75 cylinder provided at the bottom with a series of cups arranged to contain bodies of mercury 2, 3, 4, which operate as electrodes. Mounted in the top of the receptacle is a co-operating electrode 5 of some suitable material such as iron, artificial graphite or the like. This electrode is supported from a leading-in conductor 6 which is protected throughout its length by a protecting sleeve 7 of non-conducting material. Leading-in 80 wires 8, 9 and 10 are also provided for making electrical connections with the respective mercury electrodes 2, 3, and 4. The alternating current supply mains, from which the current supplied to the vapor rectifier or converter 85 is derived, are indicated at 11 and 12. One of these mains is connected to the electrode 2 and the other to electrode 4 and through the translating devices to the electrode 5. A switch 13 serves however to interrupt the 90 connection with the electrode 4 for a purpose hereinafter to be mentioned. The middle mercury electrode 3 constitutes one of the main electrodes of the rectifier and is connected through an inductance coil or reactance 95 14 with the supply main 11. In the circuit between the main 12 and the main electrode 5 are connected the translating devices or apparatus to which it is desired to supply the unidirectional or rectified current 100 derived through the instrumentality of the apparatus described. The current-consuming or translating devices may of course be 105

of any desired character either all alike or of different varieties as desired. As illustrative of such current-consuming devices I have indicated diagrammatically a storage battery at 15, lamps at 16, and a motor at 17.

In starting up the apparatus, the circuit of the supply mains 11 and 12 is closed so that the electrodes 2 and 4 are in electrical communication with the source. The switch 13 is also closed. The mercury in the three cups is then caused by suitable means to flow so that for an instant the three bodies of mercury 2, 3 and 4 are in electrical contact. This result may be accomplished in a variety of ways such for example as by slightly shaking the receptacle, in which case the three bodies of mercury momentarily overflow the bounds which separate them, one from the other, and come into momentary contact with each other. As soon as the agitation thus caused subsides, the mercury separates across the dividing walls between the cups as at 18 and 19 and thus interrupts the contact momentarily formed and so produces electrical arcs across the two bridges or walls at 18 and 19. The switch 13 may then be opened, which thereupon has the effect of causing the arc between the electrodes 4 and 3 to be transferred to the main body of the receptacle 1 and to thereafter take place between the upper electrode 5 and the electrode 3. After the apparatus has been thus started, and whether the current from the mains flows into the electrode 4 with the switch 13 closed, or into the electrode 5 with the said switch opened, a unidirectional current flows in the rectifier. This unidirectional current is utilized in the consumption circuit, the character of which has already been described.

In explaining the action of the apparatus, let it be supposed that with the switch 13 closed a positive wave, or, perhaps more correctly speaking, half period of current, flows from the electrode 4 to the electrode 3 and thence through the inductance coil 14 and back to the source. As soon as the current in the mains tends to reverse in direction, the current across the electrodes 4 and 3 ceases. Before this happens the electromagnetic energy stored up in the inductance coil 14 through the passage therethrough of the previous half wave of current discharges through the circuit including the electrodes 2 and 3. This flow of current, according to well known laws, is in the same direction as the current which, so to speak, produced the electromagnetic charge of the inductance coil. A current discharge or arc therefore takes place from the electrode 2 to the middle electrode 3. During the time that no current flows from the supply circuit, the inductance coil 14 supplies current to the rectifier. The arcs occurring in the rectifier

during overlapping time intervals serve as starting means for each other and so keep the rectifier in operation.

The translating devices may be connected in series with the inductance coil, as at 105, 70 in Fig. 5, and then receive current which instead of being in the form of a series of intermittent pulsations is nearly continuous, a result which is accomplished by the storing and restoring of energy in the inductance 75 coil alternately with the flow and periods of cessation of flow of current in the supply circuit. The translating devices may also be placed in series with the electrode 4 in Fig. 1, in which case they receive a pulsating 80 or intermittent unidirectional current. This arrangement is shown in Fig. 6 in which the translating devices are indicated at 106.

The rectifier may operate with the arcs or current flow taking place entirely in the 85 bottom of the receptacle 1 but, as has been indicated, the current flow or arc between the electrodes 3 and 4 may be transferred to the main body of the receptacle 1 by opening the switch 13. This may be of advantage by reducing the amount of mercury vapor in the tube and thus making the arc more stable. The translating devices may then be placed in circuit with the main electrode 5 as indicated. 95

In the arrangement shown in Fig. 1, only waves of a given polarity derived from the source of supply are utilized, waves of the opposite polarity being suppressed. In order to utilize both waves of current, the arrangement shown in Fig. 2 may be used. In this case the receptacle 20 is substantially the same as the receptacle 1 in Fig. 1, except however that it is provided with two upper electrodes 21 and 22 instead of a single electrode as 5 in Fig. 1. Two inductance coils 23 and 24, connected in series with each other, are employed instead of one. A circuit containing the translating devices indicated for example at 25 is connected between the junction between the inductance coils 23 and 24 and the lower or coöperating main electrode 26. The two electrodes 27 and 28 are connected respectively through switches 29 and 30 to the supply mains 31 and 32. In starting up the rectifier substantially the same procedure is gone through as in the case of the rectifier described in Fig. 1. Displacement of the mercury may be performed in either case by manual means as described or by automatic means such for example as shown in Fig. 7 in which a solenoid 107 external to the rectifier operates upon a mercury-displacing float 108 to raise or lower the level of the mercury 109, thus joining or separating at will the bodies of mercury in the mercury-retaining cups at the bottom of the receptacle. When the two arcs have been formed at the bottom of the receptacle 20, Fig. 2, the current flow may be trans- 130

ferred to the upper main electrodes 21 and 22 by opening the respective switches 29 and 30. The operation is in a certain sense a duplication of that described in connection with Fig. 1. Thus for example while a wave of current from the source is flowing for example into the electrode 22 through the rectifier and then back to the source through the translating devices 25 and the inductance coil 24, the coil 24 is receiving a charge of electromagnetic energy. As soon as the half wave of current commences to decrease in value, the inductance coil 24 commences to discharge and prolongs this flow of current until a current wave of opposite polarity from the source flows from the main 32 through the electrode 21, then through the rectifier and, after passing through the translating devices, returns through the other or supplemental inductance coil 23. This inductance coil is therefore in its turn charged so that upon a change of polarity of the supply mains it prolongs the current flow through the rectifier until an arc again passes, as before, between electrodes 22 and 26.

In both of the arrangements shown in Figs. 1 and 2 the continuous operation of the apparatus is dependent upon the fact that before one arc or discharge ceases to flow, another one tends to come into existence. The presence of an arc in the envelop at the time there is a tendency for another arc to form, enables the latter arc to come into existence by supplying mercury ions which create a conducting medium for the latter arc. The separate arcs therefore mutually enable each other to start and are dependent upon each other for their existence. If the arcs were to be reduced in number to one, that one also would cease to flow since, as will be understood from what has already been said, the current would stop flowing for one half wave and when it should start again there would be no mercury ions or conducting medium in the envelop thus preventing a continuance of the flow until again started by the initial production of ionized vapor.

In the arrangement shown in Fig. 2 the symmetrical utilization of the energy derived from the alternating current source is such that the resulting current flow in the circuit carrying the rectified current is almost absolutely steady. The flow of energy in the translating devices is therefore substantially constant. Inasmuch as the power factor of the current supplied is found to be practically unity, the pulsating flow of power in the supply circuit has been changed into a constant flow of power in the consumption circuit through the energy storing and restoring action of the inductance coils 23 and 24.

Instead of using main electrodes such as

21 and 22 in the upper part of the rectifier and transferring the arcs thereto from the starting electrodes, I may confine the field of activity in the rectifier to the space immediately about the lower electrodes. An arrangement for effecting this purpose is shown in Fig. 3 which is substantially the same as Fig. 2 except that the upper electrodes have been omitted together with the leads extending thereto. The supply mains are shown at 35 and 36 and across these mains are connected the inductance coils 37 and 38. The receptacle 39, of substantially the same form as that shown in the previously described figures, is provided at its lower portion with the three mercury electrodes 40, 41 and 42. The consumption circuit, indicated generally at 43, has one lead connected to the middle electrode 41 and the other to the junction between the two inductance coils. The starting and operation of the arrangement is substantially the same as that shown in Fig. 2. In this instance however the upper portion of the chamber 39 is utilized as a condensing chamber for cooling the mercury vapor and thus preventing the voltage of the rectifier from becoming too high and thus rendering its operation unstable. To assist in securing stability of operation, I connect in circuit with the mains leading to the rectifier a resistance such as indicated at 44 in Fig. 3. Similar steadyng resistances are used also in the arrangements described in connection with Figs. 1 and 2 and also in connection with the arrangements hereinafter to be described. Inasmuch as this feature is common to all of the rectifying devices, I consider it unnecessary to refer again to the use of the resistances specifically. Inasmuch however as a non-inductive resistance consumes energy, I may replace it by an inductive resistance, thus attaining stability without undue expenditure of energy. Such an inductive resistance I have indicated at 45 in Fig. 4. I have made claims to this feature of my invention in my copending application, Serial No. 267,720, filed June 30, 1905, which application is a division of the present application.

Fig. 4, which I have used to illustrate the application of an inductive steadyng means, represents a rectifier which is substantially the same in principle as that shown in Fig. 3 except that the electrodes 40 and 42, inasmuch as they operate as anodes and are therefore not required to be vaporized to sustain the flow of current, are replaced by electrodes of non-vaporizable material. The receptacle in this case assumes a substantially cylindrical aspect as shown at 46. In the lower portion of the receptacle is a relatively large body of mercury 47 which operates as the common cathode. The two corresponding anodes 48 and 49 of iron,

graphite or the like, are supported from the top of the receptacle as indicated, and the supporting conductors are surrounded by protecting tubes 50 and 51 of insulating material. The inductance coils or energy-storing devices are indicated at 52 and 53 and are connected in series with each other across the supply mains 54 and 55. The anodes 48 and 49 are connected respectively to the supply mains and the cathode 47 to the junction between the inductance coils as shown. Suitable leading-in wires are employed for the purpose of conveying current through the walls of the envelop or receptacle. To start the rectifier, the level of the mercury 47 is raised so as to touch, and then separate from, the anodes 48 and 49 thus starting the arcs, the operation of which has already been described in some detail. The contact between the mercury and the upper electrode may be effected by shaking the receptacle or by some electrical or otherwise actuated mechanism for raising or lowering the level of the mercury, the precise details of the arrangements used being susceptible of considerable variation.

In the preceding description I have referred chiefly to the use of inductance coils as the agency for storing and restoring energy but it is to be understood that I may employ in place thereof any other suitable energy-storing or reactance-possessing devices. In other words, my invention when considered in its broader aspect is not to be limited to any particular form of energy-storing device. Moreover, although I have indicated in a general way the manner in which I at present believe my invention to operate, I do not advance these theories as absolute facts, or hold myself responsible for their accuracy.

What I claim as new and desire to secure by Letters Patent of the United States, is,

1. The combination of an exhausted envelop, electrodes therefor, one at least of which is of vaporizable material, a source of single-phase current connected to said electrodes, means for causing a continuous succession of current waves to flow from said source through said envelop, and a consumption circuit fed by the current passing through said envelop.

2. The combination of an exhausted receptacle, a plurality of electrodes of non-vaporizable material, a coöperating vaporizable electrode, means for impressing electro-motive forces of opposite polarities upon said non-vaporizable electrodes, a return circuit leading from the vaporizable electrode, a current consuming device or current-consuming devices in said circuit, and means for causing alternate pulsations of current to take place between said non-vaporizable electrodes and the vaporizable electrode.

3. The combination of an exhausted en-

velop, a source of single-phase alternating current, non-identical paths through said envelop for current from said source, and a current-consuming device or devices traversed by the current passing through said envelop.

4. The combination of an exhausted envelop or receptacle, a source of single-phase alternating current, separate paths through said receptacle for current from said source, means for causing current of the same polarity to flow alternately in said paths, and current-consuming means external to said receptacle for utilizing the energy of the current flowing through said receptacle.

5. The combination of an exhausted envelop, electrodes therefor, a source of single-phase current connected to said electrodes, means for causing a continuous succession of unidirectional current waves to flow from said source through said envelop, and means external to the envelop for utilizing the unidirectional current.

6. The combination of a source of single-phase alternating current, a vapor rectifier connected across said source for utilizing one polarity wave of current from said source, and supplemental means for causing energy due to waves of the other polarity to pass through said rectifier.

7. The method which consists in causing unidirectional waves from an alternating current source to flow through a vapor conducting medium which is non-conducting for waves of opposite polarity, causing the waves thus flowing to traverse an energy-storing device, causing current discharges from said energy storing device to bridge over the zero points in said waves so that the resulting current is continuous, and passing the resulting current to a consumption circuit.

8. The combination of a source of single-phase alternating current, a current consuming means, and vapor rectifying means for rectifying both polarity waves of the alternating current and sending the rectified current to said current consuming means.

9. In a current rectifying device, a negative electrode, a plurality of positive electrodes, a source of alternating current having mains connected to said positive electrodes, a consumption circuit extending from said negative electrode, and an inductance device in series in said circuit.

10. A current rectifying device, comprising a negative electrode, a plurality of positive electrodes, a consumption circuit extending from the negative electrode, and an inductance device in circuit with said negative electrode.

11. A current rectifying device, comprising a negative electrode, a plurality of positive electrodes, a consumption circuit extending from the negative electrode, and an

energy storing and restoring device in circuit with said negative electrode.

12. The combination of a single phase vapor rectifier including as a part thereof a reactance in series with the circuit of the rectified current, and current-consuming means in series with said reactance.

13. The combination of a vapor rectifier including as a part thereof an inductance in the circuit of the rectified current, and current-consuming means in series with said inductance.

14. The combination of an exhausted envelop, a source of single-phase alternating current, and means for causing current derived from said source to flow continuously in said envelop.

15. The combination of a source of single-phase alternating current, an exhausted envelop, electrodes therefor, and means operated by current from said source for causing a unidirectional flow of current from said source through said envelop.

16. The combination of a source of alternating current, an envelop adapted to contain a vapor conducting-medium, and means for deriving an alternating current from said source and for transmitting the energy of said current through said conducting medium.

17. The combination of an envelop, a source of alternating current, means for generating in said envelop a plurality of overlapping supplemental or starting arcs by energy derived from said source, and means dependent upon the presence of said starting arcs for initiating the main current flow or arc in said envelop.

18. The combination of an exhausted envelop, a plurality of anodes, a cathode, reactances connected respectively between the cathode and the anodes, and a source of alternating current connected to said anodes.

19. The combination of an exhausted envelop, a plurality of anodes, a cathode, energy storing and restoring devices connected respectively between the cathode and the anodes, and a source of alternating current connected to said anodes.

20. The combination of an exhausted envelop, a cathode, anodes located adjacent to said cathode, a plurality of anodes located at a distance from said cathode, a source of alternating current, means associated with said source for producing overlapping arcs between said cathode and its adjacent anodes, and means for transferring the seat of operation of said arcs to the space between said cathode and the remaining anodes.

21. The combination of an exhausted envelop adapted to contain a vapor-conducting-medium, main electrodes therefor, supplemental electrodes therefor, a source of alternating current, means associated with

said source for producing overlapping arcs in said envelop from said supplemental electrodes, and means for transferring the arcs to the main electrodes.

22. The combination of an exhausted envelop, a source of single phase alternating current, and means for supplying current from said source to said envelop so that the flow of power in the envelop is substantially continuous while the flow of power from the source is pulsating.

23. The combination of an exhausted envelop, a source of single-phase alternating current, and means for supplying current from said source to said envelop so that the flow of power in said envelop is substantially continuous.

24. The combination of an envelop adapted to contain a vapor-conducting-medium, a plurality of electrodes, one at least of which is of vaporizable material, a source of alternating current, inductance coils connected in series with each other across mains leading from said source, means for conveying current between a vaporizable electrode and a point in the circuit between said reactance coils, and connections from said source to a plurality of other electrodes.

25. The combination of an envelop or receptacle, electrodes therefor, one at least of which is of vaporizable material, a source of alternating current, and means for generating or producing in said receptacle arcs or electric discharges, one receiving its energy directly from said source, and the other indirectly.

26. The method of causing a substantially continuous flow of power through a vapor conducting-medium, which consists in deriving alternating current from a single-phase source, causing current from said source to flow through said medium, and storing and re-storing energy derived from said source so as to produce a substantially continuous expenditure of energy in said medium as distinguished from a pulsating flow of power derived from said source.

27. The method which consists in causing unidirectional waves from an alternating current source to flow through a given path in a vapor conducting-medium which given path is non-conducting for waves of opposite polarity, causing the waves thus flowing to traverse an energy-storing device, and causing current discharges from said energy storing device to flow in said medium so as to bridge over to a greater or less extent the intervals during which no current from said source flows over said path.

28. The combination of a source of alternating current, a vapor conducting-medium traversed by current directly from said source, and an energy storing device for receiving energy while current is flowing from said source through said medium and for de-

livering the energy thus stored to a circuit including said medium during such intervals as the current from said source is not flowing directly to a circuit including said medium.

29. As a means for maintaining an arc between substances which would not ordinarily arc with alternating current, the combination with electrodes of such substance or 10 substances, of energy-storing means for storing the energy of the alternating current when the current is not in a proper direction to pass through the arc and then re-storing it to the arc in the proper direction.
- 15 30. The combination with a source of single phase alternating current, electrodes connected to said source of such nature and so related to each other as to prohibit an alternating flow of current in the form of an 20 arc between said electrodes, and means for deriving an alternating current from said source and causing said alternating current to flow between said electrodes in the form of direct or unidirectional current arcs.
- 25 31. The combination of a source of alternating electro-motive force, a medium initially non-conducting for current from said source, electrodes communicating with said medium and connected to said source, and 30 means for causing current waves of both polarities to flow from said source through said medium.
32. The combination of an exhausted envelop, electrodes therefor, one at least of 35 which is of vaporizable material, a source of single-phase current connected to said electrodes, and means for causing a continuous succession of current waves to flow from said source through said envelop.
- 40 33. The combination of a source of alternating current, a vapor conducting medium having a cathode and a plurality of anodes connected to said source, and a device having 45 reactance interposed in a lead between said source and one of said anodes.
34. The combination of a source of alter-

nating current, a vapor conducting medium having a cathode and a plurality of anodes connected to said source, and a steadyng device consisting of a reactance traversed by 50 current passing from said source to one of said anodes.

35. The combination of a source of alternating current, a vapor conducting medium in circuit with said source, and means possessing reactance interposed between said source and said medium and operating to prevent cessation of current in said medium at times when no current flows from said source.

60 36. The combination of a source of alternating current, a vapor conducting medium in circuit with said source, and means possessing reactance traversed by current passing in said medium and operating to prevent cessation of current in said medium at times when no current flows from said source.

70 37. The method of regulating an electric circuit in which a vapor converter of the character described is interposed, which consists in storing energy by means of a suitable inductance or inductances, and preventing by the same means a fall of potential below the operative limit of the converter.

75 38. The method of regulating an electric circuit in which a vapor converter of the character described is interposed in the alternating current portion of the circuit, which consists in storing energy by means of 80 a suitable inductance or inductances in the direct current portion of the circuit, and preventing by the same means a fall of potential below the operative limit of the converter.

85 In witness whereof, I have hereunto set my hand this 20th day of March, 1903.

EZECHIEL WEINTRAUB.
